UNITED STATES PATENT OFFICE.

WILLIAM MACGREGOR, OF NIAGARA FALLS, NEW YORK, ASSIGNOR TO THE CARBORUNDUM COMPANY, OF NIAGARA FALLS, NEW YORK, A CORPORATION OF PENNSYLVANIA.

APPARATUS FOR SMOOTHING AND POLISHING STONE.

1,327,440.

Specification of Letters Patent. Patented Jan. 6, 1920.

Application filed February 9, 1918. Serial No. 216,209.

To all whom it may concern:

Be it known that I, WILLIAM MACGREGOR, a subject of the King of Great Britain, residing at Niagara Falls, in the county of Niagara and State of New York, have invented 5 a new and useful Improvement in Apparatus for Smoothing and Polishing Stone, of which the following is a full, clear, and exact description, reference being had to the accompanying drawings, forming part of this specification, in which—

Figure 1 is a plan view of a machine embodying my invention.

Fig. 2 is a side elevation of the same.

Fig. 3 is a section on the line III—III of Fig. 2.

Fig. 4 is an end elevation, and

Fig. 5 is a sectional view showing a special form of grinding head.

20 My invention relates to machines for smoothing and polishing marble, concrete and other kinds of natural and artificial stone, and is particularly useful in the rubbing and smoothing of blocks and slabs of 25 marble after they have been sawed from quarried blocks, for the purpose of smoothing the sawed surfaces and giving them a uniform plane surface for further treatment in honing and polishing. This operation 30 is technically known as rubbing.

The regular practice heretofore has been to place the blocks or slabs on a rubbing bed consisting of a large flat circular table of cast iron revolving at a speed of about 2000 35 peripheral feet per minute. Such beds vary from 6 to 18 feet in diameter. The slabs are laid on the bed and are held in fixed position thereon. A supply of sand and water is fed to the center of the bed and this sand 40 works toward the periphery, cutting the marble to a smooth surface as it is drawn thereunder.

The process is a slow and expensive one and requires a constant supply of new sharp sand.

45 My invention is designed to provide smoothing and polishing apparatus in which the work can be done much more rapidly than with the old process, which will give a smoother and better finish, and by which the output may be greatly increased. My invention 50 also improves the general working conditions, making them quicker and more healthful.

Referring to the accompanying drawings, 55 in which I have shown a preferred embodiment of my invention, the numeral 2 designates a reciprocating table or carrier for the piece A of marble or other material to be smoothed. This table or carrier is mounted 60 in V-grooves 3 on a bed 4, and is designed to travel backward and forward in the manner of the work carrier or table of a metal planing machine. 5 designates a rack and pinion mechanism for reciprocating the 65 table and which is driven from the shaft 6 in any manner well known to the operation of planing machines, this driving means forming no part of my invention. The shaft 6 may be driven by means of the pulleys 7. The reversal of the table is also effected in any usual manner.

70 Side posts 10 are rigidly connected to the bed 4 and carry a cross-head or carriage 12 above the table 2, this cross-head or carriage being mounted for vertical movement in suitable guides 13. The vertical movement of the head is effected by means of the screws 14 actuated manually by a suitable hand wheel or lever applied to the shaft 15, 75 which is connected by gears 16 with a cross-shaft 17 connected by bevel gears 18 with each of said screws; or any well known automatic feed such as used in a metal planer 80 may be employed.

85 19 designates a vertical shaft which is journaled in suitable bearings 20 on a cross-head 12, being supported on said cross-head by a collar 21 so as to move vertically therewith. At its upper end portion this shaft 90 carries a bevel gear wheel 22 through which the shaft can slide while maintaining a driving connection therewith and which is driven by a bevel gear 23 on the shaft 8, which is provided with fast and loose driving pulleys 9. On the lower end of the shaft 19 is a head or chuck 24 in which is secured a grinding wheel 25, which is preferably composed of carborundum blocks or sections 95 suitably secured in the head or chuck and which is of sufficient diameter to span the full working width of the table 2; or at least of sufficient diameter to span the entire width of the pieces of stone to be rubbed.

100 The operation will be readily understood. 105 The reciprocating carriage carries the stone underneath the grinding wheel, which is rotated at the desired rate of speed, prefer-

ably from 2000 to 5000 peripheral feet per minute, the cross-head being fed down as may be required.

The use of this machine effects a great

- 5 saving in time over the old method owing to the high rate of speed at which the grinding wheel may be driven; and as the cutting action of said wheel is limited only by the amount of power that can be supplied to it,
 10 the amount of marble cut off in a given time will greatly exceed that with the old machine heretofore used. The grinding wheel covers the entire slab or block of stone during each traverse and leaves a finish which is very
 15 much smoother than can be obtained with the old form of rubbing beds. By using a grinding wheel of carborundum, the output results are greatly increased, owing to the very superior cutting power of this material
 20 as compared with that of sand. The general working conditions are also rendered more healthful.

A further advantage of my invention is the obtaining of a surface of superior
 25 smoothness without ridges or lines, such as are left by the sand in the old form of machines.

I am aware that it has been proposed heretofore to finish marble by using a plurality
 30 of grinding heads which are arranged together to cover the whole surface of the marble slab as it was passed under such heads. This method, however, has not proven successful because the heads follow
 35 the original windings in the slab and rise and fall with the hard and soft spots therein, giving an irregular finish. This is entirely overcome by using a single solid wheel covering the whole width of the slab.

40 In Fig. 5 I have shown a form of grinding wheel or head, which is of special advantage where successive smoothing and polishing operations are employed to give a successively higher degree of smoothness
 45 to the stone.

In this figure of the drawings, 26 designates a hollow sleeve shaft which is journaled in the cross-head 12^a, which may be similar to the cross-head 12 before described,
 50 and which is shown as being driven by the gears 22^a and 23^a in the same manner as the shaft 19 before described. This sleeve shaft has secured to its lower end a main head or chuck 27 in which is secured an annular
 55 grinding ring 28. This grinding ring may, for instance, be composed of carborundum blocks of #40 grit, such as would be used for roughing cut.

29 designates another grinding ring arranged concentrically within the ring 28 and carried by a head or chuck 30 which is secured to the lower end of the shaft 31, which is keyed to the hollow shaft 26 to rotate therewith, while capable of vertical movement therein. The ring 29 may be com-

posed of carborundum of a much finer grit, such as No. 150 and can be secured to the chuck or head 30 by cement, or other suitable means.

The ring 29 can be raised and lowered 70 relatively to the ring 28 by suitable means, such as a hand wheel 32 engaging the upper threaded end portion 33 of said shaft and bearing against the upper end of the sleeve shaft 26. The latter is arranged to 75 slide vertically through the gear 22^a on the driving key 34.

In using this form of head, in the first operation, the coarse grinding ring 28 is lowered by lowering the cross-head 12^a into 80 the position for the roughing cut, the fine grinding ring 29 being at this time raised sufficiently within the head or chuck 27 so that its grinding surface will not contact with the work. After the roughing cut the 85 fine grinding ring 29 is lowered to a position where its grinding surface is below the level of the grinding surface of the ring 28.

After these first two cuts, the grinding heads can be removed and another head substituted having suitable means for effecting the later operations of honing and shining or glossing. For this purpose the outer ring may be composed of carborundum blocks of FF grit, and the final shining or 95 glossing ring may consist of a felt mop. In connection with this mop oxalic acid crystals may be used, or a mixture of oxalic acid and putty powder; or any other polishing materials of known or suitable character. 100

I do not desire to limit myself to the particular construction and arrangement of the parts which I have herein shown and described, since, obviously, many changes can be made therein within the spirit and scope 105 of the appended claims, thus any suitable driving means may be employed for rotating the grinding wheel; the grinding parts of the latter may be of any suitable material; various means may be employed for 110 moving one of the grinding rings relatively to the other where a combined form of head is employed; and a greater number of concentric grinding rings of different degrees of cutting or smoothing action may 115 be used.

I claim:

1. A grinding or polishing head having a plurality of concentric rotating grinding or polishing members, and means for moving said members relatively to each other in a direction normal to the planes of their work-engaging faces; substantially as described.

2. A grinding or polishing head, comprising a plurality of concentric grinding or polishing rings concentrically mounted on a single vertical guiding shaft, and means for moving said rings vertically relatively to each other; substantially as described. 130

3. In a machine of the class described, a grinding head having a plurality of concentric grinding or polishing elements, means for raising and lowering said elements simultaneously, and means whereby at least one of said elements can be raised or lowered with respect to another element; substantially as described. 15

4. In a machine of the character described, a hollow shaft, an annular grinding or polishing element carried thereby, another grinding or polishing element arranged con- 20

centrically within the first named element, a rod or shaft connected thereto and secured to the first named shaft to rotate therewith, and means for raising and lowering the second named shaft to thereby adjust the position of the second named grinding element with respect to the first named grinding element; substantially as described.

In testimony whereof, I have hereunto set my hand.

WILLIAM MacGREGOR.
